UNITED STATES PATENT OFFICE.

JOSIAH P. ROSS, OF LIVERMORE, KENTUCKY.

DRAINTILE CLEANER.

Application filed May 17, 1928. Serial No. 278,555.

This invention relates to drain tile cleaners, and the invention has for an object the provision of a device which operates as a scraper or fork for dislodging deposits in 5 conduits, such as drain or tile openings; and the invention has for an object the provision of novel means whereby the scraper is oscillatably mounted on a bar or element and provided with means for limiting its 10 movement in one direction and bracing it while it is in operative position, the said device being provided with means whereby the scraper can be forced over the deposit and then set to operate in the manner be- 15 fore stated.

It is a further object of this invention to provide a resilient element operative to restore the scraper to operative position and to provide means for protecting the said 20 resilient element against deposits which would interfere with its operation; and it is furthermore an object to protect such resilient element from other injury during the operation of the cleaner.

25 With the foregoing and other objects in view, the invention consists in the details of construction, and in the arrangement and combination of parts to be hereinafter more fully set forth and claimed.

30 In describing the invention in detail, reference will be had to the accompanying drawings forming part of this application, wherein like characters denote corresponding parts in the several views, and in 35 which—

Figure 1 illustrates a view in elevation of a cleaner embodying the invention;

Figure 2 illustrates a similar view at right angles to that of Fig. 1;

40 Figure 3 illustrates an enlarged detail view of a part of the device, partly in section;

Figure 4 illustrates a sectional view on the line 4—4 of Fig. 1, omitting the structure 45 in advance of the handle; and

Figure 5 illustrates a detail view of one of the scrapers.

In describing the element which is employed to dislodge the deposits in a conduit, 50 it will be referred to as a scraper, although obviously, it may take the form of a blade or fork, so that this general term is to be understood as including any element which might be employed to disturb or dislodge 55 the deposit and to move it as the device is manipulated.

The illustrated embodiment of the invention includes an advance bar or head 6 having a fin or projection 7 at one edge preferably undercut at the end, as shown at 8, to 60 form a clearance for an anchor 9, here shown as an eye, to which one end of a resilient element 10, such as a spring may be anchored. The projection 7 acts as a guard for the spring anchorage as the device is 65 pushed into a drain, or when otherwise manipulated, and it is shown that the opposite end of the spring is connected to an anchor 11 carried by a shank 12 of the scraper 13. The shank extends into a slot 70 14 of the element 6 and it is oscillatable on a pivot 15 extending transversely of the slot. The shank is shaped to form a shoulder 16 which abuts the surface of the bar or element 6 and this limits the movement of the 75 scraper under the influence of the resilient element and affords a resistance to the movement of the scraper as the device is manipulated for the purpose of dislodging deposits in a drain. The shank may also be 80 provided with an adjustable element 17 in the nature of a screw that is threaded in the shank and this screw constitutes an abutment which when it engages the wall 18 of the slot will act to limit the movement 85 of the scraper in one direction.

The resilient element or spring 10 is housed in telescopically mounted inner and outer tubes 19 and 20, respectively, the former of which has its end secured to the 90 anchor 9 and the latter of which has its end secured to the anchor 11 in appropriate manner. As the scraper swings on its pivot, therefore, the telescopic elements will slide 95 on each other, according to the direction of movement of the scraper.

The element 6 preferably is provided with a threaded socket 21 which receives an end of the handle bar 22 and the opposite end of the said handle bar may constitute a 100 mounting for a blade or shovel 23 having a socket 24 into which the handle bar extends with a suitable joint between them for maintaining them together. These parts are preferably threaded at the joint and the 105 blade or shovel may be removed for the purpose of applying additional sections of handles when it is desirable to increase the length of the handle.

The handle bar is also supplied with a 110 hand grip or handle 25 having a cuff or collar 26 which is slidable on the handle bar

and, through the employment of a set screw 27 threaded in the cuff, the handle may be secured at different positions of adjustment.

Figure 5 illustrates a scraper having tangs 5 28 and this is supposed to have a shank similar to the shank 12 in order that it can be mounted on a pivot 15 and this is illustrative of a construction alternate to that of a plain blade.

10 I claim:

In a drain cleaner, a bar, a scraper having a shank pivotally mounted on the bar,

a shoulder on said shank for engaging the bar and limiting the movement of the scraper in one direction, a resilient element anchored to the shank of the scraper and to the bar in front of the scraper, telescopically mounted elements encasing the resilient element, a projection on the front end of the bar for protecting the said resilient element and its anchorage, and a handle bar connected to the first mentioned bar in rear of the scraper.
